INVENTOR

Carson B. Boulton.

BY

ATTORNEY

UNITED STATES PATENT OFFICE.

CARSON B. BOULTON, OF OKLAHOMA, OKLAHOMA.

TROUSERS-STRETCHER.

1,250,783.

Specification of Letters Patent.

Patented Dec. 18, 1917.

Application filed June 18, 1915. Serial No. 34,845.

To all whom it may concern:

Be it known that I, CARSON B. BOULTON, a citizen of the United States, residing at Oklahoma city, in the county of Oklahoma and State of Oklahoma, have invented certain new and useful Improvements in Trousers-Stretchers, of which the following is a specification, reference being had to the accompanying drawings.

10 This invention pertains to devices for caring for trousers, so that they may be creased and kept in proper shape while being stored.

15 In addition to providing means for creasing and shaping the trousers, an object is to provide a device which can be conveniently folded for carrying or packing.

20 Other objects and advantages of the invention will be set forth in the ensuing description.

The accompanying drawings show one embodiment of the invention in practical form.

25 Figure 1 is an elevation view of the device opened outward to or toward the position in which it is used in the trousers.

30 Fig. 2 is a similar view of the device partly folded together, and with certain slidable sleeves slipped downward to allow further folding.

Fig. 3 is a view of the device completely folded.

Fig. 4 is an enlarged sectional view taken on the line 4—4 of Fig. 2.

35 Fig. 5 is an elevation view of the device shown just below the line 4—4 of Fig. 2.

Fig. 6 is a fragmental elevation view taken in the direction of the arrow 6 of Fig. 1, but with the sleeve slipped down to 40 the position shown in Figs. 2 and 5.

Fig. 7 is an elevation view taken in the direction as Figs. 3 and 6, showing a pair of pivoted arms.

Fig. 8 is a view taken in the direction of 45 the arrow 8 of Fig. 2, Figs. 5 to 8 being on the same enlarged scale as Fig. 4.

Referring to the several figures, in all of 50 which like characters of reference designate like parts, the device includes a pair of substantially straight bars 10 which are adapted to be inserted in a trousers leg and crowded apart to stretch the cloth of the leg, the outer edges 11 of these bars being brought to a sharp angle so as to form a

crease in the cloth when left under tension.

The edges 11 of the bars 10 may be armored with sheet metal 12 in order not to be worn away or injured.

At each end of the bars 10 they are connected together by a pair of links 13 which are themselves pivoted together, one link of each pair being pivoted to one bar and the other link to the other bar.

The pivotal point of the two links 13 of each pair with each other is provided with a spring 14 which acts to open said links apart and crowd the bars 10 apart into the position shown in Fig. 1, and in order that the cloth of the trousers may not be drawn bias by the stretching action of the device the outer ends of the arms of the lower pair extend past their points of pivotal connection with the bars, as at 15, and bear against the inner edges of said bars when the latter are opened outward.

With the lower pair of links arranged in this way, the bisecting line B—B of their angle will not swing materially out of parallel with the bars 10 when the latter are opened outward, and a possible tendency to draw the cloth bias is thereby counteracted.

In folding the bars 10 into the position shown in Fig. 2, the folding is against the tension of the springs 14; and in order to hold the bars closed one of them is provided at each end of its inner edge with a hook 16, and the other bar at each end with a swinging latch 17 which may be swung into locking engagement with said hook.

Each bar 10 is cut in two at its center, as at 18, to allow it to be folded into the position shown in Fig. 3, the two sections being connected together by a link 19 which is pivoted in them by a pin 20, as best shown in Fig. 6.

When the arms 10 are unfolded to working position shown in Figs. 1 or 2, the two sections of each are held straight and rigid by sheet-metal sleeves 21, the inturned edges 22 of each sleeve engaging grooves 23 in the surfaces of the bars to hold said sleeve in place.

These sleeves 21 are arranged to forcibly and frictionally grip the bars 10 in the direction of their thickness and thereby remain in any position in which they may be left, and when it is desired to fold the bars

the sleeves are slid down from over the joints 18 as shown in Fig. 2.

Having thus described the invention, I claim:

5 In a device of the class described, a pair of bars, a pair of links arranged at each end of said bars and connecting them, resilient means associated with said links for crowding the bars apart, a hook carried by

the inner edge of one bar, and latch member pivoted to the other bar to engage said hooks.

Witness my hand this 12 day of June, 1915.

CARSON B. BOULTON.

Witnesses:

H. M. KELLEY,

FRANK P. SHEPARD.
